UNITED STATES PATENT OFFICE.

CHARLES P. STANBON, OF LYNN, MASSACHUSETTS, ASSIGNOR TO UNITED SHOE MACHINERY CORPORATION, OF PATERSON, NEW JERSEY, A CORPORATION OF NEW JERSEY.

WELT-LAYING MACHINE.

1,370,613.

Specification of Letters Patent.

Patented Mar. 8, 1921.

Application filed March 17, 1919. Serial No. 283,158.

To all whom it may concern:

Be it known that I, CHARLES P. STANBON, a citizen of the United States, residing at Lynn, in the county of Essex and State of Massachusetts, have invented certain Improvements in Welt-Laying Machines, of which the following description, in connection with the accompanying drawings, is a specification, like reference characters on the drawings indicating like parts in the several figures.

This invention relates to machines for applying a strip of stock to a blank and is herein illustrated as embodied in a machine for laying a piece of welting along the margin of a sole.

In the manufacture of McKay shoes it is commonly the practice to provide a mock or imitation welt in order to give the shoe an appearance more desirable to the trade. Welting is supplied in long strips; and it is commonly the practice to coat one side of the welting with cement and then to apply the welting to successive soles. A machine by which this applying operation may be performed is shown in the patent to McLeod, No. 957,987 and comprises an applying roll over which the welting is guided, a roll for supporting the sole during the applying operation and a knife for severing the welting when the proper length has been applied. In that machine after a sole has been operated upon, the severed end of the unapplied portion of the welting is not held in any way, with the result that when the next sole is presented to the machine the operator is obliged to place this free end properly on the sole before beginning the next welt laying or applying operation; and this preliminary placing of the severed end of the welting on the sole has to be repeated for each sole presented to the machine.

According to one feature of the present invention, means are provided for holding this severed end of the strip in position to be applied to the next sole or other blank presented to the machine. In the illustrative machine the knife is so constructed and operated that when it severs the strip at the completion of the first strip-applying operation it holds the severed end of the unapplied portion of the strip against the applying roll, in position to be applied properly to the next blank presented to the ma-

chine, and is released as soon as the presentation is completed. With this construction the operator is relieved of the necessity which hitherto existed of manually guiding the severed end of the unapplied portion of the strip to each blank at the beginning of each strip-applying operation.

This and other features of the invention, including certain details of construction and combinations of parts will be described as embodied in an illustrative machine and pointed out in the appended claims.

Referring now to the accompanying drawings,

Figure 1 is a front view, principally in section, of a machine in which the present invention is embodied;

Fig. 2 is an end elevation;

Fig. 3 is a perspective showing the mechanism for locking and unlocking the knife, and

Fig. 4 is a perspective showing a portion of the starting and stopping mechanism.

Rotatably mounted in the frame 5 of the machine is a hollow driving shaft 7 having loosely mounted thereon a driving pulley 9 to which power may be applied continuously from any suitable source. This pulley has a flat face which may be brought into contact with a ring 11 of suitable friction material carried by a driving disk 13 which is fast to the hollow shaft 7. The pulley 9 may be moved to the left into engagement with the disk 13 in either of two ways, by moving to the left a rod 14 or by turning a crank-arm 15. The rod is slideable within the hollow shaft 7 and has threaded into its outer end a cap screw 16. Between the head of this screw and the pulley 9 are located the hub 17 of the crank-arm 15 and a collar 18, the hub being loose on the shaft and the collar being slidably keyed to the shaft.

The hub 17 is thicker at the top than at the bottom, as viewed in Fig. 1, and the collar is thinner at the top than at the bottom, the two adjacent faces of the hub and the collar being complementary cam faces so arranged that when the crank-arm 15 is turned the collar will be moved to the left to force the pulley 9 into engagement with the driving disk 13. With this sort of manipulation, the rod 14 is held in the position shown. If, on the other hand, the rod is pulled to the left, the head of the cap

screw 16 will move the hub 17 and collar 18 to the left to move the pulley 9 into engagement with the disk 13. It is also possible to combine these two means for applying power:—that is, the rod may be pulled to the left sufficiently to cause the pulley to engage the disk lightly, and then the crank-arm 15 may be manipulated. As long as the crank-arm is not turned any 10 faster than the pulley 9 is rotating the shaft 7, no effect will be produced; but, by turning the crank-arm faster, the pulley 9 may be forced into more intimate contact with the disk 13 to cause the shaft 7 to rotate faster. This mechanism for controlling the rate of rotation of the shaft 7 is known as a "hand-belt-power drive," a type of which is shown in my prior Patent No. 500,438.

20 The rod 14 has threaded into its inner end a cap screw 19 which extends through the arms of a yoke formed on a bell-crank lever 20 pivoted on a fixed rod 21, two washers, one of which is a split spring-washer being loosely mounted on the screw 19 between its head and the yoke as shown. A small adjusting screw 22 is threaded through an upstanding lug on the bell-crank lever 20 and has threaded thereon a lock nut 23. A treadle rod 24 has mounted thereon a fixed collar 28 and a loose spring-pressed washer 30 between which the horizontal arm of the bell-crank lever extends. A coiled spring 32, located between the 30 frame of the machine and a collar 34 fixed to the rod, normally holds the rod 14 in the position shown. Depression of a treadle (not shown) which is connected with the rod 24 will thus apply power to the shaft 7 and release of the treadle will effect withdrawal of power.

Fast to the shaft 7 is a double gear 25, 26. When power is applied to the shaft, by pulling down upon the treadle-rod 24, a 45 brake is withdrawn from engagement with the gear 25; and when the treadle-rod is allowed to rise, the brake is applied to the gear. This brake mechanism, which is shown best in Fig. 4, comprises a rod 36 carried by a bell-crank lever 38, said lever, like the bell-crank lever 20 being pivoted about the rod 21 and having its horizontal arm received between the collar 28 and the yielding washer 30. The portion of the arm 50 of the lever 38 which is received between the collar 28 and washer 30 is somewhat thicker than the corresponding portion of the bell-crank lever 20. In a socket in the end of the rod 36 is a friction plug 40 backed by a 55 spring which is somewhat compressed in the position of parts shown. With this construction the plug 40 will be withdrawn from the gear 25 just before power is applied to the gear and will be moved back 60 into the position shown just after power is

withdrawn from the gear. The purpose of this brake is to facilitate the stopping of the machine at just the desired point with respect to the work.

The members of the double gear 25, 26 are adapted to mesh with a small gear 27 and a large gear 29, the two last-named gears being mounted upon a common hub which is slidably connected with the shaft 31 of the upper or applying roll 33 by a key 35. A rod 37 slidable in the frame of the machine and having a downwardly turned end extending into a groove in the hub of the gears 27, 29 furnishes means for sliding the gears on the shaft, said rod being held in either one of two positions by a spring-pressed pawl 39. In the position shown, the gears 25 and 27 are in mesh, but by pulling the rod 37 to the right these gears may be disengaged and the gears 26, 29 caused to drive the shaft 31 at a lower speed.

The shaft 41 of the lower or supporting roll 43 is rotatable in a sleeve-bearing 45 which is pivoted on trunnions mounted in brackets on the frame of the machine, the axis of the trunnions being shown at 47 and one of the brackets at 49. Near its outer end the bearing 45 is pivoted at 51 to a treadle-rod 53, a spring 55, located between 95 a collar on the rod and a washer resting upon the frame of the machine, serving at all times to urge the bearing 45, and with it the supporting roll, upwardly so as to hold the work yieldingly against the applying roll. A gear 57 fast to the shaft 31 meshes with a gear 59 of equal size fast to the end of the shaft 41, the teeth of these gears being of a length sufficient to permit lowering of the roll 43 about the pivot 47 when the treadle-rod 53 is pulled downwardly to permit removal of a finished piece of work and insertion of another sole blank between the rolls.

The welting 100 which has previously 110 been coated on one side with cement, is led from any suitable source over a guide pulley 61 and down through a curved guide 63 which causes it to run over a portion of the surface of the applying roll 33, the 115 guide delivering the free end of the welting at a point just in advance of the bite of the rolls 33, 43. An idle roll 44 holds the welting against the guide pulley 61. An adjustable edge gage 65 is provided to facilitate 120 guiding the work as it passes through the machine.

In the operation of the machine the lower roll 43 is depressed to permit a sole to be placed between the rolls, the end of the welting 100 is positioned properly on the sole, and the roll 43 released. Power is then applied to the rolls to rotate them, and the sole is guided properly by the operator, the rate of rotation of the rolls being controlled, if 130

desired, by manipulation of the crank-arm 15. The welting is thus laid or applied along the margin of the sole beginning at a point on the shank of the sole at one side 5 thereof running around the toe and ending at a point approximately opposite on the other side. At this point the clutch is released, and the machine comes to rest. Hitherto it has been customary next to sever 10 the welting on a bevel either with a hand-knife or with a treadle-operated knife such as that shown in the patent to McLeod. In either case the free end of the unapplied welting was left unsupported so that, when 15 the next sole was presented to the machine, the operator was obliged to guide the free end into proper place on the sole before starting the machine again. In the present machine the welting is severed, and 20 the free end held against the applying roll while the supporting roll is lowered to permit removal of the finished work and insertion of the next sole, and is then automatically released when the supporting roll is 25 allowed to rise. In the illustrative machine both the severing and the holding of the welting are accomplished by the knife.

The segmental knife 67 is clamped by a screw 69 in a suitable holder 71, the holder 30 being pivoted at 73 to a block 75 which is adjustable in a guideway in a carrier 77. After loosening the screw 69, the knife may be adjusted in and out of the holder 71; by manipulating the adjusting screw 79 the 35 holder may be adjusted about the pivot 73, and by manipulating the thumb screw 81 the block 75, and with it the knife, may be raised and lowered. These adjustments are to provide for welting of different thickness 40 and to obtain the proper relation between the operative end of the knife and the upper roll 33 so that when the knife is swung, in a manner presently to be described, into the cutting-off position shown in Fig. 2, the severed 45 end of the unapplied welting will be held firmly against the face of the roll 33 in position to be applied properly to the next sole presented to the machine. In Fig. 2, the severing operation has just been completed.

50 The next step is to depress the treadle (not shown) of the rod 53 thereby lowering the roll 43. The sole 200, with the welt attached may then be removed from the machine and another sole located properly between the 55 rolls. The treadle is then released whereupon the knife is swung upwardly to release the end of the welting and to permit the welt laying or applying operation to be carried out again.

60 The carrier 77 is fast to the outer end of a rock-shaft 83, the inner end of which is clamped by a pinch-screw 85 to the hub of an arm 87, said arm being pivoted at 89 to a head 90 fast to the upper end of a treadle rod 91. A coiled spring 93 having its lower end

resting upon the frame of the machine and its upper end abutting against the collar 95 on the rod 91 holds the knife normally in raised inoperative position. The head 90 has a lug or tooth over which a spring- 70 pressed locking pawl 97 moves when the treadle rod 91 is pulled downwardly. The effect of this construction is to lock the knife in the position shown in Fig. 2 when the lower roll 43 is depressed to permit removal of the work, the severed unapplied end of the welt thus being pinched between the surface of the cutter adjacent to its cutting edge and the welt applying roll 33. In order to disengage the pawl 97 when the roll 43 rises under the influence of the spring 55, a ratchet wheel 99 fast to the end of a stem 101, which is rotatable in the frame of the machine, has inclined side teeth or projections 103 which are adapted successively to engage a shoulder on the pawl and force the pawl back out of engagement with the head 90. In order to turn the ratchet 99, a pawl 105 is pivoted to a boss on the sleeve-bearing 45 of the shaft of the lower 90 roll 43 and is held in contact with the ratchet by a coiled spring 107. Consequently, when the bearing 45 is swung downwardly, the pawl 105 rides over the peripheral teeth of the ratchet; but, when the bearing is forced 95 upwardly by the spring 55, the ratchet is turned, and one of the high portions of the side teeth 103 engages the shoulder on the locking pawl 97 to disengage it from the head 90 and thereby permit the 100 spring 93 to rock the shaft 83 and move the knife to inoperative position. This frees the end of the welting. The side teeth 103 on the ratchet are so constructed and arranged and the rotation of the ratchet is 105 such that whenever the ratchet is at rest the locking pawl 97 is free to engage the lug on the head 90 if the lug is brought into position to be engaged.

Although the invention has been set forth 110 as embodied in a particular machine, it should be understood that the invention is not limited in the scope of its application to the particular machine which has been shown and described.

Having thus described my invention, what I claim as new and desire to secure by Letters Patent of the United States is:

1. A machine for applying a strip of stock to a blank, having in combination, a strip-applying roll, a blank-supporting roll, means for rotating said rolls, and means for severing the strip and holding the severed end of the unapplied portion of the strip in position to be applied to the next blank presented to the machine.

2. A machine for applying a strip of stock to a blank, having in combination, a strip-applying roll, a blank-supporting roll, means for rotating said rolls, means for

severing the strip and holding the severed end of the unapplied portion of the strip in position to be applied to the next blank presented to the machine, means for causing 5 movements of separation and approach of the rolls, and means responsive to one of these movements for releasing the severed end.

3. A machine for applying a strip of 10 stock to a blank, having in combination, a strip-applying member, a blank-supporting member, and means for severing the strip and holding the severed end against the applying member in position to be applied 15 to the next blank presented to the machine.

4. A machine for applying a strip of 20 stock to a blank, having in combination, an applying roll, a supporting roll, and means for severing the strip and holding the severed end of the unapplied portion thereof against the applying roll.

5. A machine for applying a strip of 25 stock to a blank, having in combination, an applying roll, a supporting roll, means for severing the strip and holding the severed end of the unapplied portion thereof against the applying roll, and means for releasing said end preparatory to applying a strip to another blank.

30 6. A machine for applying a strip of stock to a blank, having in combination, an applying roll, a supporting roll, means for severing the strip and holding the severed end of the unapplied portion thereof against 35 the applying roll, and means, responsive to the bringing into operative position of a part of the machine preparatory to the operation upon another blank, for releasing said end.

40 7. A machine for applying a strip of stock to a blank, having in combination, an applying roll over which the strip runs, a blank-supporting roll, means for rotating the rolls, a cutter, and means for moving 45 the cutter to sever the strip after a desired amount has been applied and to hold the severed end of the unapplied portion of the strip against the applying roll in position to be applied to the next blank presented to the machine.

45 8. A machine for applying a strip of stock to a blank, having in combination, an applying roll over which the strip runs, a blank-supporting roll, means for rotating the rolls, a cutter, means for moving the cutter to sever the strip after a desired amount has been applied and to hold the severed end of the unapplied portion of the strip against the applying roll in position to 55 be applied to the next blank presented to the machine, and means for moving the cutter to release said end.

60 9. A machine for applying a strip of stock to a blank, having in combination, an applying roll over which the strip runs,

a blank-supporting roll, means for rotating the rolls, a cutter, means for moving the cutter to sever the strip after a desired amount has been applied and to hold the severed end of the unapplied portion of the strip against the applying roll in position to be applied to the next blank presented to the machine, and means, responsive to the bringing into operative position of a part of the machine preparatory to the operation 70 upon another blank, for moving the cutter to release said end.

10. A machine for applying a strip of stock to a blank, having in combination, an applying roll over which the strip runs, a blank-supporting roll, means for rotating the rolls, means for severing the strip at a point on the blank and for holding the severed end of the unapplied portion of the strip in position to be applied to the next blank, means for separating the rolls to permit withdrawing of the finished work and placing of the next blank between the rolls, and means responsive to movement of approach of the rolls for releasing said end. 75

11. A machine for applying a strip of stock to a blank, having in combination, a strip-applying roll, a blank-supporting roll, means for rotating said rolls, yielding means for holding said rolls in operative relation 80 to each other, a cutter, means for moving the cutter to sever the strip and for locking the cutter in position to hold the severed end of the unapplied portion of the strip against the applying roll, means for separating the rolls to permit removal of the finished work and insertion of another blank, and means responsive to the release of the roll-separating means for unlocking the cutter and freeing the end. 85

12. A machine for applying a strip of stock to a blank, having in combination, a blank-supporting member, a member for applying the strip to a blank, a strip-severing cutter, and means for moving the cutter 90 so that its cutting edge generates a curved surface. 100

13. A machine for applying a strip of stock to a blank, having in combination, a blank-supporting member, a member for applying the strip to a blank, a strip-severing cutter, and means for moving the cutter so that its cutting edge generates a curved surface, such that the free end of the unapplied portion of the strip is held against the applying member. 115

14. A machine for applying a strip of stock to a blank, having in combination, an applying roll over which the strip runs, a blank-supporting roll, a strip-severing cutter, and means for moving the cutter so that its cutting edge generates a cylindrical surface. 120

15. A machine for applying a strip of stock to a blank, having in combination, an 125

5 applying roll over which the strip runs, a blank-supporting roll, a strip-severing cutter, and means for moving the cutter so that its cutting edge generates a cylindrical surface, the radius of curvature of which is greater than that of the applying roll.

16. A machine for applying a strip of stock to a blank, having in combination, a strip-applying roll, a blank-supporting roll, 10 means for rotating the rolls, a cutter having a blade curved transversely of its cutting edge, a holder in which the cutter is mounted, a carrier in which the holder is mounted, means whereby the cutter may be adjusted 15 with respect to the holder and the holder with respect to the carrier, and means for rocking the cutter.

17. A machine for applying a strip of stock to a blank, having in combination, an 20 applying roll over which the strip runs, a blank-supporting roll, means for rotating the rolls, a strip-severing cutter, treadle-controlled means for causing the cutter to sever the strip, and means for locking the cutter 25 in severing position.

18. A machine for applying a strip of stock to a blank, having in combination, an applying roll over which the strip runs, a blank-supporting roll, means for rotating 30 the rolls, a strip-severing cutter, treadle-controlled means for causing the cutter to sever the strip, means for locking the cutter in severing position, means for lowering and raising the supporting roll, and means operated by raising of said roll for releasing the cutter. 35

19. A machine for applying a strip of stock to a blank having, in combination, a strip applying member, and means for sever- 40 ing the strip and pinching the severed end

of the unapplied portion thereof against the strip applying member.

20. A machine for applying a strip of stock to a blank having, in combination, a strip applying roll, means for rotating said 45 roll, and a cutter for severing the strip and pinching the severed end of the unapplied portion thereof against the strip applying roll.

21. A machine for applying a strip of stock to a blank having, in combination, a strip applying roll, blank supporting means, means for rotating said roll, and means for severing the strip and pinching the severed 55 end of the unapplied portion of the strip against the strip applying roll.

22. A machine for applying a strip of stock to a blank having, in combination, a strip applying roll, blank supporting means, a strip severing cutter, and means for moving 60 the cutter so that its edge generates a curved surface to cut the strip of stock and pinch the severed end thereof between the cutter and the applying roll.

23. A machine for applying a strip of stock to a blank having, in combination, a strip applying roll, a blank supporting roll, means for rotating the rolls, a cutter comprising a blade curved transversely of its cutting edge, a holder in which the cutter is 65 mounted, a carrier mounted for rocking movement and in which the holder is mounted, and means for rocking the carrier substantially about the axis of the curvature of the cutter blade to cut the strip of stock and 70 pinch the cut end thereof between the strip applying roll and the cutter. 75

In testimony whereof I have signed my name to this specification.

CHARLES P. STANBON.
